UNITED STATES PATENT OFFICE.

SIGMUND S. HIRSCH AND ISAAC E. SHANE, OF KANSAS CITY, MISSOURI.

FEATHER-TREATING APPARATUS.

1,110,936.

Specification of Letters Patent. Patented Sept. 15, 1914.

Application filed June 21, 1912. Serial No. 765,092.

To all whom it may concern:

Be it known that we, SIGMUND S. HIRSCH and ISAAC E. SHANE, citizens of the United States, residing at Kansas City, in the 5 county of Jackson and State of Missouri, have invented certain new and useful Improvements in Feather-Treating Apparatus, of which the following is a specification.

This invention relates to feather treating 10 apparatus, and more specially to means for laying the dust in feathers as the same are being prepared for use as pillows, bed or cushions.

With this general object in view, the invention 15 consists in certain novel and peculiar features of construction and organization as hereinafter described and claimed; and in order that it may be fully understood reference is to be had to the accompanying 20 drawing, in which:—

Figure 1, is a side elevation of a feather treating apparatus embodying our invention. Fig. 2 is a top plan view of the same.

In the said drawing, 1 is an air compressor 25 for supplying air through a pipe 2 to a tank 3, and to a pipe 4 leading into the upper end of an oil tank 5, a valve 6 controlling the passage of air from pipe 2 or tank 3 to the oil tank, and to show the pressure of 30 air in the latter, it is equipped with an ordinary gage 7. Oil may be supplied to tank 5 in any suitable manner, the means shown consisting of a funnel-mouthed pipe 8 controlled by a suitable valve 9. The oil tank 35 is provided near its lower end with discharge pipe 10 controlled by a suitable valve 11, and to indicate when the quantity of oil 40 in the tank is getting too low, said tank is provided with a device 12 corresponding to a water column.

13 is an atomizer to receive oil from pipe 10 and compressed air from a pipe 14 leading from pipe 4 or the tank 3; said atomizer being of any suitable or preferred type 45 whereby the air under pressure, passing from the pipe 14 shall efficiently and thoroughly atomize the oil forced by the air pressure in tank 5 through the discharge pipe thereof into the atomizer, the pipe 14 being 50 equipped with a control valve 15.

The atomizer discharges tangentially 55 against the interior walls of a conduit 16 through which the feathers which are to be crushed are drawn by a rotary crusher having inclined blades as disclosed at 18'. The

current created is sufficient to cause the feathers to pass for some distance along the conduit from whence they are further forced by a blower (not shown), the said conduit having a rotary device or paddle 18 whereby 60 the feathers are thoroughly agitated and distributed in order that they may be subjected to the jet of atomized oil from the atomizer 13, this treatment serving to lay the dust in the feathers, it being understood 65 that this discharge of atomized oil on the feathers may occur in the crusher, if desired.

A very light and volatile oil is employed, as the use of a heavy oil would render the further treatment of the feathers difficult 70 and furthermore would leave them in such condition that they could not be employed in high grade pillows, mattresses or cushions.

To facilitate the atomization of the oil the same is heated and to heat the same, we 75 preferably employ a steam coil 18, submerged in the oil of the tank 5, a pipe 19 controlled by a valve 20, supplying steam to the coil and a pipe 21 conducting the exhaust steam from the coil. 80

From the above description it will be apparent that we have produced an apparatus for laying dust in feathers which operates efficiently and reliably, which can be easily controlled, and which is susceptible of modification in minor particulars without departing from the principle of construction defined by the appended claims. 85

We claim:

1. In an apparatus for treating feathers, 90 the combination of a conduit, means for creating a current of air through the conduit to convey the feathers therethrough and means for discharging atomized oil into the conduit, and upon the feathers while in 95 transit through the conduit.

2. In an apparatus for treating feathers, the combination of a conduit, means within the conduit for creating a current of air to 100 convey feathers therethrough and agitate the feathers while in transit, and means for discharging atomized oil into the conduit and upon the feathers therein.

In testimony whereof we affix our signatures, in the presence of two witnesses.

SIGMUND S. HIRSCH.
ISAAC E. SHANE.
